UNITED STATES PATENT OFFICE.

FRANCIS B. FAWCETT, OF KIDDERMINSTER, ENGLAND, ASSIGNOR TO
GEORGE MATTHIAS WHITTALL, OF SPRING BANK, WRIBBENHALL,
ENGLAND.

JACQUARD APPARATUS.

SPECIFICATION forming part of Letters Patent No. 569,749, dated October 20, 1896.

Application filed March 18, 1896. Serial No. 583,687. (No model.)

To all whom it may concern:

Be it known that I, FRANCIS BEST FAWCETT, of 44 Comberton Road, Kidderminster, in the county of Worcester, England, have 5 invented certain new and useful Improvements in Jacquard Apparatus Used in Weaving Brussels and Piled Carpets and other Fabrics, of which the following is a specification.

This invention relates to improvements in 10 Jacquard apparatus employed in weaving Brussels and piled carpets or rugs and other fabrics by which a greater number of lifting-cords can be operated than heretofore by a given number of needles. This is accomplished by the rearrangement of the Jacquard apparatus. Thus the holes in the trap-board are all arranged so as to trap all the lifting-cords of the face-warps in their normal or quiescent position, the untrapping being effected in all cases by the pressing in of the needles. This modification of the trap-board renders unnecessary the use of coiled springs for returning the needles to their quiescent position, as the drag of the lifting-cords suffices to move them back so soon as the needles are released from the pressure of the cords. Again, the needles are caused to work (as hereinafter described) in combination with each other in selected pairs instead of 20 independently, so that each needle is made capable of operating several lifting-cords instead of only one lifting-cord, or at the most two, as heretofore. Thus the scope of the Jacquard apparatus is largely increased without increasing its size, and fabrics can be produced having a much greater range of color or effect than is possible by the ordinary method of working the Jacquard apparatus.

40 In order to make clear the full advantages of the invention, I will proceed to explain how I propose to operate upon ten sets of face-warps, that being the maximum number of face-warps which can be conveniently contained in one dent or split of the reed.

The needles are arranged in vertical rows, there being two groups or sets in each row, each group or set numbering five needles.

The loops or eyes of the two sets of needles stand out, the one from the right-hand side 50 and the other from the left-hand side of the upper and lower groups, respectively.

For the purposes of this invention the trap or lifting board and the top board will have ten holes to each set of five needles instead of 55 only five or six, as at present, and through each hole is passed a lifting-cord, making ten cords to each set of five needles.

The cords passed through the trap-board are, in their normal position, all trapped, as 60 above stated, and ready to be raised by the lifting-board, the slotted elongation of the holes in the board being toward the front of the jacquard. Each Jacquard needle is formed with four loops or long eyes, through which 65 the lifting-cords will pass, and these loops or eyes are so disposed that the pushing back of any three needles in the one group of five needles will push nine cords out of trap and leave only one cord entrapped. This will be 70 clearly understood by reference to the accompanying drawings, wherein—

Figure 1 shows the Jacquard apparatus in end elevation, partly sectional, the needles, trap-board, and cords being suitably arranged 75 for carrying out my invention. Fig. 1^a is a diagram corresponding with Fig. 1 of the upper group or set of one vertical row of needles, illustrating the operation of those needles. Fig. 2 is a partial plan view of the trap-board. 80 Fig. 3 is a partial front elevation of the Jacquard apparatus, showing the vertical rows of horizontal needles; and Fig. 4 is a plan view of two detached needles belonging, respectively, to the upper and lower sets of one 85 vertical row.

The detached views indicate the mode of distributing the loops on the needles, so that one cord only shall be trapped at a time to secure the requisite lift of the warp-threads 90 to suit the pattern in hand. The order or arrangement, however, of the loops in the needles and the cords may be varied, as will be readily understood when the details to be presently described are fully grasped.

95 The five needles comprising the upper group

or set of one vertical row are marked, (see Figs. 1 and 1^a), respectively, 1, 2, 3, 4, and 5, and the five needles comprising the lower set are marked, respectively, 1^a, 2^a, 3^a, 4^a, and 5^a in Fig. 1.

The ten lifting-cords for the upper set of needles are marked, respectively, b' to b¹⁰, and alternating with these are the ten lifting-cords marked, respectively, c' to c¹⁰ for the lower set of five needles.

The ten holes in the trap-board for the ten lifting-cords for the upper set of five needles (see Fig. 2) are marked, respectively, d' to d¹⁰, and the ten trap-board holes for the ten lifting-cords of the lower set of five needles are marked, respectively, e' to e¹⁰. For convenience the two sets of ten holes d' to d¹⁰ and e' to e¹⁰ are arranged relatively to each other, as shown in the plan view at Fig. 2.

The loops in the needles for the lifting-cords are arranged as follows, corresponding with the ten holes d' to d¹⁰ of the trap-board: Needle No. 1 has four loops f' f² f³ f⁴, corresponding with the first four holes d' d² d³ d⁴. Needle No. 2 has four loops g' g² g³ g⁴, corresponding with the first hole d', fifth hole d⁵, sixth hole d⁶, and seventh hole d⁷. Needle No. 3 has four loops h' h² h³ h⁴, corresponding with the second hole d², fifth hole d⁵, eighth hole d⁸, and ninth hole d⁹. Needle No. 4 has four loops i' i² i³ i⁴, corresponding with the third hole d³, sixth hole d⁶, eighth hole d⁸, and tenth hole d¹⁰. Needle No. 5 has four loops j' j² j³ j⁴, corresponding with the fourth hole d⁴, seventh hole d⁷, ninth hole d⁹, and tenth hole d¹⁰.

Arranged in this manner it will be found that, as shown in Fig. 1, the loops in the needles form pairs under each of the ten holes d' to d¹⁰ in the trap-board and that each of the cords b' to b¹⁰ in passing downward through the needles must pass through two loops. For example, the cord b' in the first or front hole d' of the trap-board passes through the loops f' and g' in needles Nos. 1 and 2. The cord b² in the hole d² passes through the loops f² and h' in needles Nos. 1 and 3. The cord b³ in the third hole d³ passes through the loops f³ and i' in needles Nos. 1 and 4. The cord b⁴ in the fourth hole d⁴ passes through the loops f⁴ and j' in needles 1 and 5. The cord b⁵ in the fifth hole d⁵ passes through the loops g² and h² in needles 2 and 3. The cord b⁶ in the sixth hole d⁶ passes through the loops g³ and i² in needles 2 and 4. The cord b⁷ in the seventh hole d⁷ passes through the loops g⁴ and j² in the needles 2 and 5. The cord b⁸ in the eighth hole d⁸ passes through the loops h³ and i³ in the needles 3 and 4. The cord b⁹ in the ninth hole d⁹ passes through the loops h⁴ and j³ in the needles 3 and 5. The cord b¹⁰ in the tenth hole d¹⁰ passes through the loops i⁴ and j⁴ in the needles 4 and 5.

All the cords should lightly touch the front ends of the loops, that is, the left-hand ends

in Fig. 1 in the drawings. This can be regulated by properly setting the trap-board and other boards, as is well understood.

In preparing the cards for this arrangement of needles for every cord that is to be raised it is necessary that such holes be stamped in the design-cards A, Fig. 1^a, as will allow the two needles through which such cord passes to remain unmoved while the other needles are being driven into a position to untrap the nine remaining cords. Thus to raise the first cord b' in the case described above and shown by Figs. 1 and 1^a holes must be stamped opposite the needles Nos. 1 and 2 as the first cord b' passes through these two needles. All the other needles, namely, Nos. 3, 4, and 5, being pushed back, all the other cords, namely, b² to b¹⁰ in the set of five needles, will be pushed out of trap, for although No. 1 needle would allow the second cord b², third cord b³, and fourth cord b⁴ to remain unmoved these three cords are pushed back by the loops h', i', and j' in the third, fourth, and fifth needles, through which the cords b², b³, and b⁴, respectively, also pass. The same remark applies to any other two needles in the jacquard through which a given cord passes. By this means ten variations of the five needles may be secured by allowing them to remain stationary in the following combinations: first combination, needles Nos. 1 and 2 to remain stationary; second combination, needles Nos. 1 and 3 to remain stationary; third combination, needles Nos. 1 and 4 to remain stationary; fourth combination, needles Nos. 1 and 5 to remain stationary; fifth combination, needles Nos. 2 and 3 to remain stationary; sixth combination, needles Nos. 2 and 4 to remain stationary; seventh combination, needles Nos. 2 and 5 to remain stationary; eighth combination, needles Nos. 3 and 4 to remain stationary; ninth combination, needles Nos. 3 and 5 to remain stationary; tenth combination, needles Nos. 4 and 5 to remain stationary, and consequently the ten different cords b' to b¹⁰ may be actuated by the above combinations of the five needles numbers 1 to 5.

The lower set of five needles 1^a 2^a 3^a 4^a 5^a, which actuate the ten cords c' to c¹⁰, have their loops arranged in the same order as the loops in the upper five needles 1, 2, 3, 4, and 5, except that the loops in the lower five needles are, as shown in Fig. 1, placed a little farther from the front ends (that is, the left-hand ends on Fig. 1) of the needles to afford room for the cords c' to c¹⁰ and to provide for the corresponding holes e' to e¹⁰, alternating with the cords b' to b¹⁰ and holes d' to d¹⁰ of the trap-board. The loops are also formed upon the opposite side of the needles, as shown at Fig. 4, and the cords c' to c¹⁰ consequently pass downward on the opposite side of the needles to that on which the cords b' to b¹⁰ are placed.

It will be evident that without departing

from the nature of this invention the order of the loops on the needles may be varied and yet form the same combination of pairs of loops and secure the same result—viz., actuating the ten cords by the five needles.

What I claim is—

In a Jacquard apparatus, the combination with the lifting-cords, of a trap-board having its holes adapted to trap all the said cords in their normal or quiescent position, looped needles arranged in vertical rows two groups or sets of not less than five in each row with each loop on each needle forming with one

loop on one of the needles above or below it in the same set a selected pair through which 15 one of the lifting-cords passes, whereby the pushing back of all the needles in a set save the selected two will push all the cords of that set save one out of trap, substantially as described.

Dated the 3d day of March, 1896.

FRANCIS B. FAWCETT.
